(57) **CLAIM**

The ornamental design for a motorcycle battery box cover, as shown and described.

DESCRIPTION

FIG. 1 is a front perspective view of the motorcycle battery box cover of the present invention.

FIG. 2 is a front elevation view thereof.

FIG. 3 is a rear elevation view thereof.

FIG. 4 is a top view thereof.

FIG. 5 is a bottom view thereof.

FIG. 6 is a left side view thereof; and,

FIG. 7 is a right side view thereof.

The rear surface, front surface portions and perimeter shape of the motorcycle battery box cover shown in broken lines form no part of the claimed design.
